United States Patent Office

Des. 203,241
Patented Dec. 14, 1965

203,241

BICYCLE

Alexander B. Musichuk, Parma, Ohio, assignor to The
M. T. & D. Company, a corporation of Ohio

Filed Mar. 4, 1965, Ser. No. 84,085

Term of patent 14 years

(Cl. D90—8)

Fig. 1

Fig. 2

FIGURE 1 is a front perspective view from below of a bicycle embodying my design; and

FIGURE 2 is a rear perspective view taken from above, and on the opposite side of, the bicycle shown in FIGURE 1.

The dominant features of my design are shown in solid lines in the drawing.

I claim:

The ornamental design for a bicycle substantially as shown and described.
